TERMINAL CONNECTING TOOL WITH TERMINAL DISTORTING PROJECTION

Kenneth L. Wells, Angola, Ind.

Application January 11, 1954, Serial No. 403,105

9 Claims. (Cl. 81—15)

This invention is directed to electrical terminals and means for attaching or swaging them to conductor wires.

A significant object of the invention is to provide an improved connection between a terminal and a conductor and method for establishing such connection.

An important object of the invention is to provide for this purpose a tool embodying improved principles of design and construction and which, among other things, includes a pair of pivotally connected levers, a pair of jaw members carried by one lever in a manner whereby they can be forced together by manipulating the other lever which is adapted to engage one of the jaw members, and projection means for distorting a portion of a terminal onto the end of a conductor when the two are being forcibly clamped together by the jaws.

A particular object of the invention is to provide a sub-assembly which, among other things, includes the jaw members above referred to, and a support with fastening means extending through the support and jaw members for securing the members for movement with respect to one another and the support. This sub-assembly is adapted for detachable connection with any component of a force producing means, such as one of the levers alluded to above.

A specific object of the invention is to provide one of the jaw members with an opening and the support with the projecting means for entry into the opening for distorting a portion of the terminal.

Another object of the invention is to provide the sub-assembly with pin means extending through the support and jaw members to assist in locating and holding the members and support in a stacked or superimposed relationship, and with resilient means connected to the pin means and engaging the support and jaw member adjacent thereto for resiliently supporting the members and cushioning the clamping action exerted by the jaws and the distortion of the terminal by the projection means.

An additional object of the invention is to provide one of the jaw members with a handle to facilitate opening of the jaws to permit entry and seating of a terminal therebetween.

A further object of the invention is to provide a sub-assembly of the character described above, which includes additional resilient means in the form of a spring secured by the fastening means against the jaw member having a handle thereon for normally resiliently holding the jaws together in a manner to assist in retaining a terminal between the jaws prior to manipulating the levers.

A still further object of the invention is to provide a tool which is of simple design and construction, sturdy and positive and efficient in action, and which offers advantages with respect to manufacture and assembly and use.

Many other objects and advantages of the invention will become apparent after the description hereinafter set forth is considered in conjunction with the drawings annexed hereto.

2

In the drawings:

Figure 1 is a top view of the tool;

Figure 2 is a side view in elevation of the tool showing the levers in a position to tilt and force the jaw members together;

Figure 3 is a partial side view of the tool showing the jaw members in an open condition to receive a terminal;

Figure 4 is an exploded view of certain of the components of the tool to exemplify details thereof;

10 Figure 5 is a transverse section taken through the jaws with a terminal in section disposed between the jaws;

Figure 6 shows perspective views of a portion of a conductor wire and the terminal which is adapted for attachment to the wire;

15 Figure 7 is a longitudinal sectional view taken through the conductor wire and terminal showing certain details with respect to the connection established therebetween; and

Figure 8 is a transverse section taken through the structure of Figure 7 illustrating other details of the connection.

20 Referring more particularly to Figures 1 through 4 of the drawing, the tool, which is adapted to be held in and manipulated by hand, comprises, among other things, a 25 pair of pressure applying members preferably in the form of two levers generally designated 1 and 2 which are pivotally connected together by a pivot 3; a support 4 carried by the lever 1 which serves as a mounting; projection means 5 carried by the support; a pair of complementary jaw members 6 and 7 secured to the support by fastening means 8 in a manner whereby the jaw members may be moved with respect to one another and to the support; locating means 9 for the jaw members; resilient means 10 interposed between the support and jaw members; and additional resilient means in the form of a spring 11 secured in superimposed relationship to the jaw member 6 by the fastening means 8.

25 Although the pressure applying members are preferably made in the form of levers as illustrated, it is to be understood that the support 4, jaw members and other components directly associated therewith constituting a sub-assembly, might be secured to any suitable mounting means which may be stationary and that any additional means suitable for the purpose may be employed to effect 30 movement of the jaws for clamping and affixing a terminal onto a conductor wire.

35 However, as exemplified in the drawing, the lever 1 constitutes the mounting means for the sub-assembly. This lever may be formed in various ways but is preferably made of metal bar stock and the same is true of the lever 2. The levers are rigid and of a sufficient size and length for convenience in handling. The forward end of lever 1 is preferably angled as indicated at 12 and is provided with a bifurcation with one end of the lever 2 disposed therein for guiding the lever 2 with respect to the lever 1. The inner longitudinal edge of the lever 2 is preferably interrupted by a circular notch 13 located in relatively close proximity to the pivot 3, the purpose of 40 which will be described in detail subsequently.

45 The support 4, preferably in the form of an elongated plate, is detachably secured against the upper surface of the lever 1 by means of a pair of screws 14 which extend through holes provided therefor in the lever and connect with threaded holes 15 provided in the support, as clearly illustrated, particularly in Figures 3 and 4. The forward end of the support is provided with the projection means 5 which is preferably made in the form of a cylindrical element having a pointed end 16 thereon. 50 The element is preferably permanently secured within a hole provided therefor in the support and as shown in Figures 2 and 3, the element is of a length to extend

through the support with its butt end bearing against the upper surface of the lever 1 so that the latter will receive some of the pressure from the element as well as the support when the tool is operated to secure a terminal to a conductor.

The jaw member 6 and 7 are elongated and of substantially the same length and, as clearly shown, the fastening means 8, preferably in the form of a rivet, extends through a hole in the rear end of the support and also through holes provided therefor in the jaw members and the spring 11. The rivet includes a head which bears against the upper surface of the lever 1 and its free end is upset to more or less loosely secure the jaw members and spring to the support 4 so that the jaw members may move in the manner described above. The rivet offers a means whereby any of the parts held thereby can be readily replaced.

A tubular part or spacer washer 17 surrounds the rivet 8 and is interposed between the support and the lower jaw member 7. The locating means 9 is preferably made in the form of a long cylindrical pin which extends through and is anchored to the lower jaw member 7 with its upper extremity extending through holes provided therefor in the upper jaw member 6 and the spring 11 and so that its lower extremity extends through holes provided therefor in the resilient means 10 and the support 4 and into a relatively large recess 18 provided in the lever 1 to provide clearance for the pin when the tool is operated in accord with Figures 2 and 3. The resilient means 10 is preferably made in the form of a piece of tubular rubber. The resilient means 10 and the washer 17 serve to maintain the jaws in a predetermined spaced relationship with respect to the support. The resilient means functions to cushion movement of the levers, jaw members and distortion of a portion of the terminal by the pin 5.

The foremost ends of the members 6 and 7 are provided with a pair of complementary jaws and, as clearly exemplified in the drawing, the jaw of the lower member 7 is shaped to provide a pair of transverse land portions 19 with a channel portion 20 therebetween. The channel is preferably provided with a round opening 21 extending transversely therethrough for receiving the pin 5 as depicted in Figure 2.

The upper member 6 is preferably formed with a pair of transverse corrugations, the crests of which constitute a pair of corresponding parallel bearing portions 22 which, in combination with the land portions 19, serve to clamp the terminal therebetween as the pin 5 distorts a portion of the terminal. It will be noted that the upper jaw also includes a channel portion 23 which is disposed opposite the channel 20 of the lower jaw. The channel portions 20 and 23 complement one another and serve to receive those portions of the terminal which receive the conductor wire. In order to facilitate opening of the jaw members the upper jaw member 6 is preferably provided with an offset handle 24 for manipulating the jaw to the position illustrated in Figure 3 to permit entry of a terminal. The spring 11, constituting the additional resilient means above referred to, serves to normally maintain the jaws in closed relationship and retain a terminal between the jaws before the levers are manipulated.

As clearly illustrated in Figures 5 through 8 the terminal is preferably substantially flat and has an extremity or tab which is formed to provide a centrally disposed longitudinal corrugation 25 substantially arcuate in cross-section. This corrugation extends outwardly from one side of the tab between planar longitudinally extending edge portions 26 and serves to provide a seat for the bare end 27 of a stranded wire conductor. The tab is also formed with a bridge portion 28 which extends outwardly from the tab in a direction opposite to that of the corrugation 25. The bridge portion is also arcuate in cross-section and also assists to provide in combina-

tion with the corrugation 25 a seat for the bare end of the wire. The formation of the bridge portion serves to provide an opening 29 which extends transversely through the corrugation 25. When the terminal is inserted between the jaws, the edge portions 26 of the tab will rest upon the lands 19 and engage the bearing portions 22 of the upper jaw, and the corrugation 25 of the lower jaw and the bridge 28 will be respectively disposed in the channels 23 and 20 of the jaws. Attention is directed to the fact that the jaw on the lower member 7 is provided with shoulders or abutments 30 adjacent the lands so that the terminal will be confined and not spread apart or become abnormally distorted during the process of securing a terminal onto the wire.

To effect the connection between the terminal and wire it is only necessary to hold the lower lever in one hand, raise the upper lever and then open the jaws by depressing the handle 24 so that a terminal may be inserted between the jaw members 6 and 7 as illustrated in Figure 5, after which the handle is released so that the spring 11 will press the upper jaw against the lower jaw to hold the terminal in place. The bare end of a conductor wire is then inserted into the seat or seats formed by the corrugation or bridge, whereupon the lever 2 is manipulated to cause such lever to engage the upper jaw member 6 in a manner whereby the pointed end 16 of the projection means will move upwardly through the opening 21 in the lower jaw to engage and gradually force or distort the bridge portion 28 of the tab into the position illustrated in Figure 7. More specifically in this regard, the pointed end 16 causes the bridge portion to buckle and form a rounded or convex portion 31 which forces strands of the conductor wire into the opening 29 as clearly shown in Figure 7 in order to provide a permanent interlock between the terminal and wire. As clearly shown in Figure 8, the upper surface of the rounded portion 31 of the bridge portion serves to more or less spread the strands of the conductor wire thereon so as to increase the contact area between the wire and terminal and thereby provide an efficient electrical connection. The terminal and jaw members are so formed that the pointed end of the projection means will force the bridge portion of the terminal upwardly to such an extent that the strands of wire on the upper surface of portion 31 will be more or less flattened into intimate bearing relationship with such portion to further insure a good electrical contact between the wire and terminal. After the connection has been effected, it is only necessary to lift up on the upper lever whereupon the terminal may be readily removed from the jaws by pulling outwardly on the conductor wire.

Attention is also directed to the fact that when the levers are directed toward one another for the purpose of securing the terminal to the wire, the jaw members will be tilted to cause compression of the resilient means 10 until the channel 20 of the lower jaw engages the support 4 on opposite sides of the pin 5. The pointed end of the pin actually begins to distort the bridge of the terminal before the lower jaw engages the support and since the resilient means is gradually compressed during this action the bridge portion is resiliently urged or eased into engagement with the pin for distortion or shaping thereby. This setup serves to place the jaws in a desirable position to better accommodate the terminal, the conductor wire to the terminal and, at the same time, allows the metal of the bridge to flow and work upwardly into proper relationship with respect to the opening 29 so that the wire will be permanently affixed to the terminal as described.

Attention is further directed to the fact that the marginal edge of the circular notch 13 in the upper lever 2 serves to receive, engage and cam the free end of the

upper jaw member 6 downwardly when lever 2 is initially moved toward the lower lever 1 and as the levers are brought closer together, the lower marginal edge of the upper lever will be caused to engage the channel 23 as shown in Figure 2. Since the end of the upper lever is received in the notch 13 during such initial movement, a good clamping or wedging action is obtained relatively close to the pivot 3 and at the same time relieves what would otherwise be an excessive thrust that would be placed on the rivet 8 by rearward movement of the jaw member.

Having thus described my invention, it is obvious that various modifications may be made in the same without departing from the spirit of the invention, and, therefore, I do not wish to be understood as limiting myself to the exact form, construction, arrangement, and combination of parts herein shown and described.

I claim:

1. A tool for attaching a terminal to a conductor comprising a pair of levers pivotally connected together, an elongated first member having a jaw, an elongated second member having a jaw cooperable with the jaw of the first member, means for securing the members to one lever for movement with respect to one another between said levers, the other lever being engageable with the second member at a location adjacent the pivotal connection for forcing the jaws together, and a projection disposed between the jaws for distorting a portion of a terminal while it is being clamped between the jaws.

2. A tool for attaching a terminal to a conductor comprising a pair of levers pivotally connected together, an elongated first member having a jaw, an elongated second member having a jaw cooperable with the jaw of the first member, means for securing the members together on one lever for movement with respect to one another between the levers, one of said jaws having an opening therein, and a projection extending from said one lever for entry into the opening and between the members, and the other lever being engageable with the second member at a location adjacent the pivotal connection for forcing the jaws together whereby the projection will distort a portion of a terminal while it is being clamped between the jaws.

3. A tool for attaching a terminal to a conductor comprising a pair of levers pivotally connected together, a support carried by one of the levers, an elongated first member having a jaw, an elongated second member having a jaw cooperable with the jaw of the first member, means for securing the members to the support between the levers for movement with respect to one another and the support, resilient means interposed between and engaging the support and first member, one of the jaws having an opening therein, a projection on said support for entry into the opening, and the other lever being engageable with the second member at a location adjacent the pivotal connection for compressing the resilient means and forcing the jaws together so that the projection will distort a portion of a terminal while it is being clamped between the jaws.

4. A tool for attaching a terminal to a conductor comprising a pair of levers pivotally connected together, a support carried by one of the levers, an elongated first member having a jaw, an elongated second member having a jaw cooperable with the jaw of the first member, means for securing the members together on the support for movement between the levers with respect to one another and the support, resilient means interposed between and engaging the support and first member, resilient means engaging the second member for urging it against the first member, one of the jaws having an opening therein, a projection on the support for entry into the opening, and the other lever being engageable with the second member at a location adjacent the pivotal

connection for compressing the first-mentioned resilient means and forcing the jaws together so that the projection will distort a portion of a terminal while it is being clamped between the jaws.

5. Means for attaching a terminal to a conductor, said means comprising a mounting, a support carried by the mounting, a projection extending from the support, an elongated first member having a jaw provided with an opening for receiving the projection, an elongated second member having a jaw cooperable with the jaw of the first member, means extending through the members and support for securing the members to the mounting for movement with respect to one another and the support, resilient means interposed between and engaging the support and said first member, and means engageable with said second member for compressing the resilient means and forcing the jaws together so that the projection will distort a portion of a terminal while it is being clamped between the jaws.

20 6. Means for attaching a terminal to a conductor, said means comprising a mounting, a support carried by the mounting, a projection extending from the support, an elongated first member having a jaw provided with an opening for receiving the projection, an elongated second member having a jaw engageable with the jaw of the first member, means for securing the members to the support for relative movement, and means engageable with said second member for forcing the jaws together so that the projection will distort a portion of a terminal

30 while it is being clamped between the jaws.

7. Means for attaching a terminal to a conductor, said means comprising a mounting, a support carried by the mounting, a projection extending from the support, an elongated first member having a jaw provided with an opening for receiving the projection, an elongated second member having a jaw cooperable with the jaw of the first member, means extending through the members and support for securing the members for movement with respect to one another and the support, a spring urging the members together, spacer means and resilient means interposed between and engaging the support and said first member, and means cooperable with said second member for compressing the resilient means and forcing the jaws together so that the projection will distort a portion of a terminal when clamped between the jaws.

8. Means for attaching a terminal to a conductor, said means comprising an elongated mounting, a projection extending from the mounting at a location between the ends of the mounting, an elongated first member having a jaw provided with an opening for receiving the projection, an elongated second member having a jaw cooperable with the jaw of the first member, means for securing the members to the mounting between its ends for movement with respect to one another, and means cooperable with said second member for forcing the jaws together so that the projection will distort a portion of a terminal when clamped between the jaws.

60 9. An assembly comprising an elongated support provided with a projection, a pair of elongated jaw members, means extending through the members and support for holding the members and support assembled so that the jaw members may be moved with respect to one another and the support, resilient means and spacer means interposed between one of the jaw members and the support, an opening provided in said one jaw member for receiving said projection so that the latter may deform a terminal placed between the jaw members, a spring secured by said extending means for urging the other jaw member against said one jaw member, and lever means for forcing the jaw members toward one another.
